Attorney

UNITED STATES PATENT OFFICE

MAX WENZEL, OF MULDENSTEIN, NEAR BITTERFELD, GERMANY

PAPER MANUFACTURE

Application filed October 17, 1929, Serial No. 400,268, and in Germany September 6, 1928.

This invention relates to apparatus for and methods of manufacturing paper, and with regard to certain more specific features, to rollers adapted to be used in couchings, pressing, glazing, calendering, wetting, coating, and other similar operations.

Among the several objects of the invention may be noted the provision of a roller of the class described which is characterized by the fact that the bandage (usually felt or other similar material) does not come loose or get out of place on the roller; the provision of a method for applying said bandage to the roller so that it will not become loosened during the manufacture of paper and the like; and the provision of apparatus of the class described which is simple in construction and durable and efficient in operation. Other objects will be in part obvious and in part pointed out hereinafter.

In prior constructions, paper rollers have been furnished with a spirally wound covering or bandage of felt or some other material. In spite of careful rolling, and tight fitting of the bandages upon the rolls (generally by means of threads, wires, ropes or the like inserted into the body of the bandage), difficulty has been experienced in keeping the bandages in place upon the rolls. This will frequently happen after the roll has been in service for a short time only, and necessitate shut-downs for repair or alteration.

The present invention, as pointed out hereinbefore in the objects, provides a roll wherein there is no tendency for such slipping to take place.

In the accompanying drawings, in which are illustrated several of the various possible embodiments of the invention:

Fig. 1 is a cross section of one form of the invention as applied to a roll, the section being taken substantially perpendicularly to the axis of the roll;

Fig. 2 is a section similar to Fig. 1, showing a second embodiment of the invention;

Fig. 3 is a section similar to Fig. 1, showing a third embodiment of the invention; and

Fig. 4 is a section similar to Fig. 1, showing a fourth embodiment of the invention.

Corresponding reference characters indicate corresponding parts throughout the several views of the drawings.

Referring now more particularly to Fig. 1, there is shown at index "d" a portion of a cylinder or roll, which is adapted to be used in the various operations hereinbefore mentioned. Upon the surface of roll "d" are a number of projections or ridges "e". These projections "e" may take the form of rabbets (as in the present embodiment) or they may be ribs, grooves, teeth, screw-like threads or the like.

Index "a" indicates the felt covering, or bandage, for the roll "d". Provided in this bandage "a" are grooves and projections "c" adapted to engage the projections "e" on the roll "d".

The projections "e" and corresponding grooves "c" are preferably made regular (parallel or the like) regardless of the form they may assume. It is desirable (from the standpoint of manufacturing the rolls) that the projections "e" be parallel to the axis of the cylinder "d", although this is not essential.

Fig. 1 illustrates a roll which is not subject to great torques and the like in operation; the tight binding of the bandage "a" alone sufficing to hold it to the roll "d", with the aid of the projections "e" and the grooves "c".

In Fig. 2 is illustrated a roll adapted to undergo heavy strains and the like. In this embodiment a wire, string, rope, or the like "b" is threaded through the bandage "a" and the ends are securely affixed to the roll "d" in order to firmly bind the bandage "a" in place.

It will be noticed that in Fig. 2 the projections "e" and the grooves "c" are different in shape from the Fig. 1 embodiment. In the

present case, splines are provided which are mounted in roll "d" and which engage the customary notches "c" in the bandage "a".

As illustrated in Fig. 3, the projections "e" need not be long, but may assume a punctiform shape, such as spikes, etc., engaging corresponding indentations in the bandage "a".

It is to be understood at this point that the invention does not comprise any particular shape of projection or groove, but includes all surface irregularities on the rolls "d" adapted to secure the bandage "a" in position.

It is not necessary that the bandage "a" be provided with grooves or indentations. With certain forms of projections "e" (see Fig. 4), the bandage may be applied without any special shaping, bound in place by wires "b" and engaged to be firmly held in position by the sharp projections "e" on the roll "d". Because of its softness, in such instances, the bandage "a" is squeezed into the projection "e". The roll, as shown in Fig. 4, is particularly applicable on paper-machines where no great pressure is required on the roll.

In view of the above, it will be seen that the several objects of the invention are achieved and other advantageous results attained.

30 As many changes could be made in carrying out the above constructions without departing from the scope of the invention, it is intended that all matter contained in the above description or shown in the accompanying drawings shall be interpreted as illustrative and not in a limiting sense.

I claim:

1. The press roller adapted for use in paper manufacture which comprises a roll, projections on the surface of said roll, a bandage covering the surface of said roll, and pre-formed indentations in said bandage adapted to receive said projections.

45 2. The press roller adapted for use in paper manufacture which comprises a roll, projections on the surface of said roll, a bandage covering the surface of said roll, and pre-formed indentations in said bandage adapted to receive said projections, said projections being substantially parallel to the axis of said roller.

55 3. The press roller adapted for use in paper manufacture which comprises a roll, projections on the surface of said roll, a bandage covering the surface of said roll, and pre-formed indentations in said bandage adapted to receive said projections, said indentations and projections being rectangular in form.

60 4. The press roller adapted for use in paper manufacture which comprises a roll, projections on the surface of said roll, a bandage covering the surface of said roll, and pre-formed indentations in said bandage adapted to receive said projections, said indentations and projections being triangular in form.

5. The press roller adapted for use in paper manufacture which comprises a roll, projections on the surface of said roll, a bandage covering the surface of said roll, and pre-formed indentations in said bandage adapted to receive said projections, said indentations and projections being rectangular in form and positioned substantially radially of the roll.

In testimony whereof, I have signed my name to this specification this 3d day of October, 1929.

MAX WENZEL.
